UNITED STATES PATENT OFFICE

GERARDO F. MARCIANO, OF PROVIDENCE, RHODE ISLAND, ASSIGNOR TO UNIVERSAL OPTICAL CORPORATION, OF PROVIDENCE, RHODE ISLAND, A CORPORATION OF RHODE ISLAND

OPHTHALMIC MOUNTING

Application filed October 1, 1928. Serial No. 309,597.

- This invention relates to an improved construction of ophthalmic mounting; and has for its object to provide in such a mounting a pair of spaced non-metallic eyewires, 5 each having an enlargement on its inner edge and a connecting bridge member having a cross bar with side arms, the ends of the side arms being attached to said enlargements by which the bridge is attached to the eyewires.
- 10 A further object of the invention is to shape the enlargements on the eyewires so as to form nose-guard members and to attach the lower end on each arm of the connecting bridge member to said enlargement.
- 15 The invention further consists in inserting the free ends of the bridge side arms into an opening in the enlargement and also to provide cooperating means on the side arms for further securing them to the eyewires.
- 20 With these and other objects in view, the invention consists of certain novel features of construction, as will be more fully described, and particularly pointed out in the appended claims.
- 25 In the accompanying drawings:
- Fig. 1 is a front view partly in section showing the ends of the bridge arms as inserted into openings in the enlargements in the eyewires.
- 30 Fig. 2 is an edge view showing the structure illustrated in Fig. 1.
- Fig. 3 is a perspective view showing the enlargement on the eyewire as forming a rearwardly-extending nose guard portion.
- 35 Fig. 4 is a detail showing the bridge member with elongated side arms; also showing these side arms as provided with tubular riveting members.
- Fig. 5 shows a section of tubing from which 40 the tubular rivets are formed.
- Fig. 6 is a perspective view showing the bridge member as provided with clamping fastening members instead of tubular rivet fastening members.
- 45 Fig. 7 shows the bridge with the end of one of its arms inserted into an opening in the enlargement of the eyewire and showing the clamping member as assisting in securing the bridge to the eyewire.
- 50 Fig. 8 is an enlarged section on line 8—8 of Fig. 7 showing the clamp as folded around the eyewire.
- It is found of advantage in the practical construction of ophthalmic mountings of this character, in some instances, particularly where the eyewires are made of a non-metallic material to form the nose-guard members integral with the inner edges of the eyewires and to form these nose guards in such a way as to provide a shoulder at their upper ends, each having an opening into which a free end of the bridge arm may extend for the purpose of connecting the eyewires together. Also, it is found of advantage in some instances to provide a second fastening 55 nearer the upper ends of the side arms to further assist in securing the bridge member to the eyewires; and the following is a detailed description of the present embodiment of my invention and showing one means by 60 which these advantageous results may be accomplished:
- With reference to the drawings, 10 designates the eyewires which in this particular construction are preferably formed of non-metallic material and are provided with enlargements 11 on their inner edges. 65
- These enlargements are preferably shaped to extend rearwardly as at 12 to perform the function of nose-guard members and each enlargement provides a shoulder 13 which has an opening or hole 14 to receive the end of its bridge arm.
- The form of bridge preferably employed in this style of mounting is herein shown as 70 having a cross bar 15 set substantially flush with the upper edges of the eyewires and provided with inwardly-curved arms 16. The end portions 17 of these arms being arranged to extend each into its opening 14 in the enlargement of the eyewire and may be secured 75 therein by cementing or other suitable means. Also it is found in some cases of advantage to provide an auxiliary fastening for the bridge member which in some cases comprises the 80 soldering of a rivet 18 which may be tubular in form, if desired, to the upper portions of the arms of the bridge member and extend these rivets thru the eyewire to be upset or riveted as at 19, against the inner surface 85

thereof, while in other instances instead of using rivets I may provide a clamp member 20 on these bridge arms which may be folded about the eyewire with the ends 21 folded inwardly, as best illustrated in Figs. 7 and 8, if desired.

By my improved construction of ophthalmic mounting, the lower ends of the bridge arms are rigidly and securely fastened to the enlargements of the eyewires and when these enlargements are shaped to form the noseguards a very neat and attractive mounting is provided.

The foregoing description is directed solely towards the construction illustrated, but I desire it to be understood that I reserve the privilege of resorting to all the mechanical changes to which the device is susceptible, the invention being defined and limited only by the terms of the appended claims.

I claim:

1. An ophthalmic mounting comprising a pair of spaced non-metallic eyewires, nose guard members integral therewith and having recesses therein, a bridge member having a pair of downwardly-extending side arms, the free end of each arm continuing its general extent into and terminating in and being secured in the recess of the corresponding nose guard member.

2. An ophthalmic mounting comprising a pair of spaced non-metallic eyewires, nose guard members integral therewith and having recesses therein, a bridge member having elongated downwardly-extending side arms secured in the recesses of said nose guard members, and means between the nose guard members and the juncture of said arms and connecting portion of the bridge therebetween for further securing each bridge arm to the associated eyewire.

3. An ophthalmic mounting comprising a pair of spaced non-metallic eyewires, nose guard members integral with said eyewires and extending rearwardly therefrom and a bridge member having elongated downwardly-extending side arms closely following said eyewires and terminating in and secured to said nose guard members.

4. An ophthalmic mounting comprising a pair of spaced non-metallic eyewires, nose guard members integral with said eyewires and extending rearwardly therefrom and each having an opening therein, a bridge member having elongated downwardly extending side arms closely following the eyewires, each being secured in said openings in said nose guard members, and cooperating fastening means on said bridge arms and eyewires at a point above and removed from said nose guard to further assist in securing the bridge to the eyewires.

In testimony whereof I affix my signature.

GERARDO F. MARCIANO.
